United States Patent Office

Des. 195,659
Patented July 9, 1963

195,659

SUPPOSITORY

Charles L. Weckesser, 20 Hayes St., Norwich, N.Y.

Filed Nov. 24, 1961, Ser. No. 67,700

Term of patent 14 years

(Cl. D83—1)

FIG. 3

FIG. 1

FIG. 2

FIG. 4

FIG. 1 is a front elevational view of a suppository showing my new design;

FIG. 2 is a side elevational view thereof;

FIG. 3 is a top plan view thereof; and

FIG. 4 is a bottom plan view thereof.

The rear and side not shown are the same as the respective front and side elevational views shown.

I claim:

The ornamental design for a suppository, as shown and described.
